UNITED STATES PATENT OFFICE.

JOHN M. FEDDERS, OF BUFFALO, NEW YORK, ASSIGNOR TO FEDDERS MANUFACTURING COMPANY INC., OF BUFFALO, NEW YORK, A CORPORATION OF NEW YORK.

RADIATOR CORE.

Application filed December 16, 1926. Serial No. 155,267.

This invention relates to a core which is more particularly designed for use in radiators which are used in connection with gas engines for cooling the water employed for preventing excessive heating of the engine, such as radiators employed on automobiles and other automotive vehicles.

It is the object of this invention to provide a core for such radiators which will yield a greater radiating efficiency for a given amount of metal and which can be assembled rapidly and accurately without exercising great care.

In the accompanying drawings:—
15 Figure 1 is a fragmentary front elevation of a radiator core embodying one form of my invention.

Figure 2 is a vertical transverse section taken on the correspondingly numbered line 20 in Figure 3.

Figure 3 is a top plan view of a portion of the radiator core embodying this invention.

Figure 4 is a horizontal section taken on line 4—4 Fig. 2.

Figure 5 is a vertical longitudinal section taken on line 5—5, Fig. 2.

Figures 6 and 7 are perspective views of one section of a radiator unit made in accordance with my invention.

Similar characters of reference indicate like parts in the several figures of the drawings.

In its general organization, this radiator core comprises a plurality of water passages 10 which in the instant case are arranged vertically, and a plurality of air tubes 11, 12, which are arranged between said water passages.

40 Each of the water passages 10 is formed between the opposing sides of two sheet metal strips so that this passage is arranged vertically. Each of these sheet metal strips is preferably made of very thin copper or similar metal and is provided at its opposite vertical edges with laterally off-set flanges 13, which are adapted to engage with corresponding flanges 13, of a companion strip, while the intermediate part or body of this strip recedes and forms an upright wall 14 which is spaced apart from the companion wall 14 of an adjacent metal strip and forms with the same an upright water passage, conduit, or pipe 10 which is flattened and extends with its length fore-and-aft of the radi-

ator core. The off-set flanges 13, 13 at opposite longitudinal edges of the two co-operating strips of metal are securely connected with each other by soldering or otherwise to form a leak-tight joint between the same for preventing the escape of water from the core. Each off-set edge flange 13 of these radiator core units is provided at regular intervals with locking beads 8, 9, which project alternately in opposite directions so that the concave side of one set of beads are arranged on one side of the respective flange and the convex sides of the other set of beads are arranged on the same side of this flange. These beads of the several core units are so arranged that upon assembling a plurality of such units the convex faces of the beads of each unit will engage with the concave faces of the beads of an adjacent unit and thereby securely interlock these units and hold the same against lengthwise displacement relatively to each other. By means of these interlocking beads the several units of a core can be assembled very quickly and held in the proper position relatively to each other and when the interlocked flanges of the units are connected by soldering, a core is obtained having increased strength and not liable to give way under the severest strains to which the same may be subjected while in service.

At intervals, each of the sheet metal strips is provided with laterally projecting loops which are so constructed that the metal of the same is integrally connected with the walls of the water passages, and form a plurality of air tubes between adjacent water passages, whereby the heat which is conducted from the walls of the water passages to these air tubes is absorbed by the air passing through the same and thereby operates to reduce the temperature of the water which is passing through the water passages. Although these air tubes may be of various forms in cross section, the same are preferably of hexagonal form as shown in Figs. 1 and 2.

Each of these laterally projecting loops of a metal strip or unit is bent to form one complete air tube 11 of hexagonal form 105 which has two of its opposing flat sides arranged horizontally at the top and bottom of each tube thereof. On that longitudinal side of each air tube 11 next to the companion wall 14 and flanges 13 of the respec-

tive air tube, the loop forming a complete air tube 11 is connected by means of two webs 15—15, with the wall 14 and flanges 13 of the respective metal strip so as to be connected integrally therewith, as shown in Figs 1 and 2. On the opposite longitudinal side of each complete air tube 11, the same is provided with a bead, the opposite ends of which are provided with laterally projecting lugs 16 which engage with the off-set flanges 13 on the opposing wall of an adjacent water tube, while the intermediate edge portion of this bead is provided with a longitudinal recess 17 which receives the laterally bulging or receding wall 14 of this last mentioned water tube.

In the assembled position of a plurality of units of this character, the air tubes of one strip are intercalated with the air tubes of an opposing strip of an adjacent water tube and the air tubes of these two strips engage each other at their upper and lower flat sides or facets, and the longitudinal bead of each of these strips engages with the wall and off-set flanges of the other strip.

The joint between the webs 15—15 of each loop is closed by solder so as to form a leak-tight joint there-between, and the beads of the air tubes on one strip are connected with the wall of an opposing strip, and the several air tubes of two adjacent units are connected with each other by solder, thereby securely connecting the several parts of the radiator core and not only preventing the same from leaking, but also forming a very rigid structure which is not likely to give way and cause leakage under severe strains.

When two units are thus assembled, the complete air tubes 11 are arranged in a vertical row and these in connection with the opposing walls of two adjacent strips, form two vertical rows of half tubes 12, adjacent to the outer sides of the water tube walls. When a plurality of such units are assembled, the half air tubes on opposite sides of each water tube present the appearance of complete air tubes, so that a radiator core when viewed from the front, as shown in Fig. 1, presents a honey-comb appearance in which each of the cells is of hexagonal form.

In order to preserve the hexagonal appearance of the several cells of the radiator core and still permit cross circulation of air between the several air tubes for promoting the cooling effect of the same, each of the air tubes only engages the opposite ends of its upper and lower sides with the corresponding parts of adjacent air tubes, as shown at 18.

In order to permit cross circulation of air from one air tube to another within the body of the core the central parts of the facets of each air tube, preferably the upper and lower facets thereof, are provided with air openings 20 which are so located that when

the several units are assembled these air openings of adjacent units register with each other and provide lateral communication between the longitudinal passages of the same.

The metal displaced during the formation of the cross circulation openings 20 of the complete air tubes is not completely removed from these tubes but is merely severed by transverse slits or cuts 21 adjacent to opposite ends of each complete air tube and the metal between the transverse slits of each tube is deflected inwardly in the form of a semi-tubular fin or baffle having a substantially vertical wall 22 connecting at its outer edge with one longitudinal edge of the respective air opening 20, and an inclined wall 23 connected at its outer edge with the other longitudinal edge of said air opening and connected at its inner edge with the inner edge of the companion vertical wall 22. The metal of this fin is stretched while displaced into this form. The two fins on opposite sides of each air tube are arranged reversely to each other so that the vertical wall 22 are parallel and the two inclined walls 23 are parallel but spaced apart. By this means a Z-shaped space is formed within each complete air tube which permits of making the same readily on a mandril of corresponding shape and then easily withdrawing this mandril, thereby simplifying the manufacture of the core. By providing the upper and lower sides of each complete air tube with air openings of the character described and utilizing the metal displaced by the formation of these openings as radiating fins or baffles, the amount of dead metal in the core is reduced to a minimum because the metallic engagement of adjacent air tubes is confined to the ends thereof to preserve the hexagonal or honeycomb appearance of the core, thereby securing the maximum radiating efficiency for the amount of metal used.

I claim as my invention:

1. A radiator core having a plurality of water passages and a plurality of air tubes arranged between said water passages, each of said water passages having opposing walls formed between two strips of sheet metal which have their opposite longitudinal edges off-set to form flanges engaging one another and their intermediate walls spaced from each other, and each of said strips being provided at intervals with laterally projecting loops forming air tubes, and the air tubes of one of said strips being arranged in the space between similar air tubes of an adjacent strip, and the flanges of adjacent wall strips being provided with interlocking concavo-convex beads.

2. A radiator core having a plurality of water passages and a plurality of air tubes arranged between said water passages, said air tubes having parts thereof deflected to form cross circulation openings therein and

also semi-tubular radiating fins, and each fin having a vertical wall connected at its outer edge with the respective air tube at one edge of an air opening thereof and an 5 inclined wall connected at its outer edge with the opposite edge of said opening and connected at its inner edge with the inner edge of said vertical wall.

3. A radiator core having a plurality of 10 water passages and a plurality of air tubes arranged between said water passages, said air tubes having parts thereof deflected to form cross circulation openings therein and also semi-tubular radiating fins, and each fin 15 having a vertical wall connected at its outer edge with the respective air tube at one edge of an air opening thereof and an inclined wall connected at its outer edge with the opposite edge of said opening and connected 20 at its inner edge with the inner edge of said vertical wall, each of said air tubes being provided with two of such fins and the inclined walls of said fins being parallel but spaced from each other.

4. A radiator core having a plurality of 25 water passages and a plurality of air tubes arranged between said water passages, each of said water passages having opposing walls formed between two strips of sheet metal 30 which have their opposite longitudinal edges engaging one another and their intermediate parts spaced from each other, and each of said strips being provided at intervals with laterally projecting loops forming air 35 tubes, each of said air tubes being integrally connected on one longitudinal side with one strip and engaging its opposite longitudinal side with an adjacent strip, and each tube being provided internally with a semi-tubu- 40 lar radiating fin.

5. A radiator core comprising a plurality of water passages and a plurality of air passages arranged between the water passages, each of said water passages being formed between two sheet metal strips provided with 45 off-set flanges at their longitudinal edges which engage each other while their intermediate parts are spaced apart, and each of said strips being provided at intervals with laterally projecting loops forming air 50 tubes, the tubes of each strip being complete and arranged between similar tubes of an adjacent strip and forming therewith partial air tubes which alternate with the complete tubes, and each complete tube being provided 55 internally with semi-tubular radiating fins.

6. A radiator core comprising a plurality of water passages and a plurality of air 60 passages arranged between the water passages, each of said water passages being formed between two sheet metal strips provided with off-set flanges at their longitudinal edges which engage each other while their intermediate walls are spaced apart, and each of said strips being provided at 65 intervals with laterally projecting loops forming air tubes, and the air tubes of one strip being arranged between the air tubes of an adjacent strip, and the air tubes of one strip having their ends engaging with 70 the corresponding ends of an air tube of an adjacent strip, while the intermediate parts of said air tubes are provided with registering air openings, and internal semi-tubular 75 radiating fins consisting of metal displaced by the formation of said openings.

In testimony whereof I hereby affix my signature.

JOHN M. FEDDERS.
